Primary Examiner — Cynthia Ramirez*Assistant Examiner* — Xavier Marti-Santos(74) Attorney, Agent, or Firm — Schiff Hardin LLP(57) CLAIM

The ornamental design for a table setting template, as shown and described.

DESCRIPTION

FIG. 1 is a top view of a table setting template showing the first embodiment of my design;

FIG. 2 is a top view of a second embodiment;

FIG. 3 is a top view of a third embodiment;

FIG. 4 is a top view of a fourth embodiment;

FIG. 5 is a top view of a fifth embodiment;

FIG. 6 is a top view of a sixth embodiment;

FIG. 7 is a top view of an seventh embodiment;

FIG. 8 is a top view of an eighth embodiment;

FIG. 9 is a top view of a ninth embodiment; and,

FIG. 10 is a top view of the embodiment shown in FIG. 1, in condition of use.

The broken lines in FIGS. 3–10 are to show portions of the table setting template which form no part of the claimed design.
